UNITED STATES PATENT OFFICE.

EMERSON CHARLES McFADDEN, OF SHORT HILLS, NEW JERSEY.

ERASER FOR TYPE-WRITERS.

No. 852,191.

Specification of Letters Patent.

Patented April 30, 1907.

Application filed January 28, 1907. Serial No. 354,462.

To all whom it may concern:

Be it known that I, EMERSON CHARLES McFADDEN, a citizen of the United States, and a resident of Short Hills, in the county 5 of Essex and State of New Jersey, have invented a new and Improved Eraser for Type-Writers, of which the following is a full, clear, and exact description.

This invention is an improved eraser for 10 typewriters, and is designed to render writing invisible as produced by the machine, without the need of rubbing it from the paper, as is the usual practice; but effecting the erasing by reproducing coincident therewith the characters desired to be erased and in an ink of the same color as the background of the paper or other material on which said characters appear. This is accomplished by shifting the typewriter carriage back to the 15 point where the writing to be removed or error begins, and after inserting between the machine ribbon and paper my improved eraser comprising a ribbon inked in the color of the background of the paper, the error is 20 repeated by striking the proper keys.

Reference is to be had to the accompanying drawings forming a part of this specification, in which similar characters of reference indicate corresponding parts in all the figures.

30 Figure 1 is a front elevation of one embodiment of my invention; Fig. 2 is an edge view of the same; Fig. 3 is an elevational view corresponding to Fig. 1, but with the ribbons removed; Fig. 4 is a face view of the uninked ribbon; Fig. 5 is a like view of the inked ribbon, and Fig. 6 is a cross section through the ribbons shown in Figs. 4 and 5 when attached.

In carrying out my invention, I employ a 40 suitable holder for the ribbons, the preferred embodiment of which consists of a spring fork, preferably made of a single piece of wire 1 bent upon itself at its center, as shown in Figs. 1 and 3, with the wire formed into a fork 45 at its free ends, comprising spring arms 2 separated a suitable distance, and each provided with a hooked extremity 3. At an intermediate point of the holder, the handle end thereof is constructed with an offset portion 4, as best shown in Fig. 2, said offset portion adapting the holder to be conveniently located in position when in use.

In connection with the holder is an uninked ribbon 5 and a ribbon 6, which are 55 sewed or otherwise secured together at op-

posite edges, as indicated at 7 in Figs. 1 and 6. These ribbons are of such extent that when applied to the spring arms 2, as indicated in Fig. 1, they will draw said arms together, thus adapting the holder to keep the 6 ribbons stretched under slight tension, said tension being insufficient to cause the ribbons to be punctured or torn when struck by the typewriter keys. The hooks 3 of the arms 2 prevent the ribbons from slipping therefrom when applied to the holder.

To erase "or ink out" the error or other characters produced by the typewriter, the eraser is inserted with the ribbon 6 adjacent to the paper or other material on which said 70 characters appear, it, of course, being understood that the ribbon 6 is inked in the same color as the background of the paper. With the ribbon 6 covering these characters, the error is repeated coincident therewith by 75 striking the proper keys, thus acting to color the characters the same, or substantially the same as the color of the paper on which they are produced, and thereby rendering them practically invisible.

The uninked ribbon 5 not only forms in connection with the ribbon 6 a loop adapted to be held on the arms 2, but also shields the ribbon 6 from the typewriter ribbon and prevents the ink of the latter from being stamped 85 thereon.

The word "color" as used in the foregoing description, as also in the claims hereunto annexed, is intended to cover both white and black.

It is obvious that a construction embodying my invention widely differing from the construction described, may be made within the scope of the appended claims; and I claim all such as fall within the scope thereof.

Having thus described my invention I claim as new and desire to secure by Letters Patent:

1. An eraser for inking out characters produced by a typewriter or the like, comprising 100 an inked ribbon of the same color as the background of the paper on which said characters appear, and spring arms for holding said ribbon in an outstretched position.
2. An eraser for inking out characters produced by a typewriter or the like, comprising 105 a holder with spring arms, and an inked and uninked ribbon secured at opposite edges, carried by said arms.
3. An eraser for inking out characters as 110

produced by a typewriter or the like, comprising a holder with spring arms, the latter having hooked extremities, and an inked and an uninked ribbon secured at opposite edges, 5 carried by said arms.

4. A process for erasing characters as produced on paper or other material by a typewriter, which consists in reproducing in a color corresponding to the color of the paper, 10 the same characters by the typewriter on said paper coincident with the characters desired to erase.

5. A process for erasing characters as produced on paper or other material by a typewriter, which consists in covering said characters with a ribbon inked in the color of the background of the paper, and then repeating 15 the same characters by the typewriter on said paper coincident with the characters desired to erase.

6. An eraser for rendering invisible the characters produced on paper or other material by a typewriter, comprising an inked ribbon of a color corresponding to the paper on 20 which said characters are produced, and

means for holding said ribbon in an outstretched position.

7. An eraser for rendering invisible the characters produced on paper or other material by a typewriter, comprising an inked ribbon of a color corresponding to the paper on 30 which said characters are produced, and an uninked ribbon for shielding one side of said inked ribbon.

8. An eraser for rendering invisible the characters produced on paper or other material by a typewriter, comprising an inked ribbon of a color corresponding to the paper on 35 which said characters are produced, an uninked ribbon for shielding one side of said 40 inked ribbon, and means for holding said ribbons in an outstretched position.

In testimony whereof I have signed my name to this specification in the presence of two subscribing witnesses.

EMERSON CHARLES McFADDEN.
